(57) **CLAIM**

The ornamental design for a mountable box for electronic components, as shown and described herein.

DESCRIPTION

FIG. 1 is a back perspective view of a mountable box for electronic components according to our new design;

FIG. 2 is a front perspective view of the mountable box for electronic components of FIG. 1;

FIG. 3 is a bottom plan view of the mountable box for electronic components of FIG. 1;

FIG. 4 is a first side elevation of the mountable box for electronic components of FIG. 1;

FIG. 5 is a second side elevation of the mountable box for electronic components of FIG. 1, opposite the first side;

FIG. 6 is a third side elevation of the mountable box for electronic components seen of FIG. 1, which is a quarter-turn from the first side;

FIG. 7 is a fourth side elevation of the mountable box for electronic components seen of FIG. 1, opposite the third side; and,

FIG. 8 is a top plan view of the the mountable box for electronic components of FIG. 1.

Broken lines showing in the figures illustrate portions of the mountable box for electronic components that form no part of the claimed design.
